UNITED STATES PATENT OFFICE.

CHARLES A. NASH, OF CHICAGO, ILLINOIS, ASSIGNOR TO SEYMOUR STEDMAN, OF CHICAGO, ILLINOIS.

SIGNALING SYSTEM.

Application filed October 25, 1920. Serial No. 419,290.

To all whom it may concern:

Be it known that I, CHARLES A. NASH, a citizen of the United States, residing at 2309 Archer Ave., Chicago, in the county of Cook 5 and State of Illinois, have invented a new and useful Improvement in Signaling Systems, of which the following is a specification.

My invention relates to improvements in 10 signaling systems, and more especially to a direct current signaling system. My object is to provide means by which a relatively high voltage direct current service line may be made to energize a relatively low voltage 15 signaling circuit.

The invention will be fully understood from the following specification taken in connection with the accompanying drawings, in which Figure 1 is a diagrammatic view of 20 a signaling system designed in accordance with the invention, Fig. 2 is a top plan view of a part of the mechanism, and Fig. 3 is a view of a modified form of device.

Referring to the drawings, the numeral 1 25 designates a relatively high voltage direct current circuit, as for example, a 110 volt city service line. In series with this line is a timing switch S' connected on one side to one of the direct current circuit wires by the 30 wire 30 and on the other side by the wire 31 to a pole changing device, indicated in general by 4 and adapted to direct the flow of current alternately through the wires 5 and 6. One of the wires 5 and 6 is connected to 35 each end of a primary coil P of a transformer 7. A return is afforded from the center of the primary coil P through the wire 8 back to the direct current circuit.

The transformer 7 is also provided with a 40 secondary winding S. As is shown diagrammatically upon the drawings, the number of turns in the secondary winding S is much less than the number of turns in the primary winding 3, so that the transformer operates 45 as a step-down transformer, the proportionate number of turns in the winding being calculated to give the desired voltage for the actuation of the signaling device to which it is connected.

50 In series with the secondary coil S is a signaling circuit leading through the wire 10 to a push button switch 65 or similar device, thence to a signaling apparatus such as, for example, the bell B. This circuit leads

from the bell B through the wire 11 to the 55 timing switch S² through this switch and back by the wire 12 to the other end of the secondary coil S. A shunt circuit is taken off of this signaling circuit by the wire 13 leading from the wire 10 to the time switch 60 S², thence by the wire 14 to a small battery M, thence by the wire 15 through the electro-magnet 16, and thence by the wire 17 back to the wire 11.

A shunt circuit from the two sides of the 65 timing switch S' is also provided by means of the wires 19 and 20 which carry the switch G in series with the circuit formed by them. The switch G is adapted to be closed by movement of the lever F which carries 70 near its end an iron disk 22 in close proximity to the pole piece 23 of the electro-magnet 16. The lever F is made of spring metal so that it will normally take the position shown in the drawing (to open the switch G) unless 75 a current through the electro-magnet 16 draws the disk 22 close to the pole piece 23 to close the switch G.

The operation of the pole changer 4 is as follows. Current flows from one side of the 80 direct current service line, through the wire 30, through the switch G or time switch S', and through the wire 31 to the breaker bar 40 by which it is conducted to the contact point 41, from which a small part of it is 85 conducted by the wire 42 through the electro-magnet 43, and thence by the wire 6' back to the other side of the direct current service line. The greater part of the current, however, is taken from the contact point 41 by 90 the wire 6 to one end of the primary coil P of the transformer 7. The breaker bar 40 carries an iron disk 44 lying in close proximity to the pole piece 45 of the electro-magnet 43. As soon as current flows through 95 the electro-magnet 43 the disk 44 is drawn toward the pole piece 45 causing the breaker bar 40 to break the electrical connection with the contact 41 and make a circuit with the contact 46 causing the current to flow 100 through the wire 5 to the other end of the primary coil P of the transformer 7. Current through the electro-magnet 43 is thereby cut off permitting the spring 50 to again draw the breaker bar 40 back to again make 105 contact with the point 41. The result of this action will be to cause rapid vibration of the breaker bar 40 between the contacts 41 and

46 thus sending current alternately from the two ends of the primary coil P to its center and out through the wire 8. It is obvious that the flows of current from the two ends 5 of the primary coil in opposite directions toward the center will energize the transformer 7. A supply of electrical energy at low potential is thereby obtained from the secondary winding of this transformer for 10 the actuation of the signaling apparatus.

Connected to the breaker bar 40 is a pawl 51, the end of which is adapted to engage with teeth on the ratchet wheel 52 as shown diagrammatically in 51. This device is so 15 constructed that vibrations of the breaker bar 40 between the contacts 41 and 46 will cause the end of the pawl 51 to engage with the teeth on the ratchet wheel 52 to cause rotation of this ratchet wheel in the direction indicated by the arrow. Rotation of 20 the ratchet wheel in a reverse direction is prevented by the spring pawl 54.

The ratchet wheel 52 is mounted on a shaft 56 which carries a drum 57 on which 25 are mounted three cam surfaces 58, 59 and 60 adapted to operate respectively the three timing switches S', S² and S³. The construction of these parts is shown in plan, partly diagrammatically, in Fig. 2, in 30 which the view of the ratchet wheel 52 in Fig. 1 is taken as indicated by the line 52, and the three views of the timing switches S', S² and S³, respectively, by views taken as indicated by the three lines S', S² and S³.

35 In the operation of the device the timing switches S' and S² are normally open, and the timing switch S³ closed. The switch G is also normally open, and likewise the push button switch 65. When the parts are in 40 this position, it is obvious that there will be no current flowing through any of the wires or circuits. When it is desired to operate the bell or other signaling device B the push button switch 65 is closed, causing current to flow from the battery M through the switch S³, the wire 13, the wire 10, the push button switch 65, the bell B, the wire 11, the wire 17, the magnet 16, and the wire 15 back to the battery M.

45 The flow of the current through the magnet 16 causes the pole piece 23 to attract the disk 22 causing the switch G to be closed. The closing of the switch G causes current to flow from the direct current circuit 50 through the wires 30 and 20 to the switch G, thence by the wires 19 and 31 to the pole changer 4 through which it flows, as described above, causing most of the current to alternate between the two ends of 55 the primary coil to the wire 8, thence back to the high voltage direct current circuit.

60 The operation of the pole changer as described before, causes rotation of the wheel 52 and drum 57 on which is carried the three cam surfaces 58, 59 and 60. These

cam surfaces are so arranged that rotation of the drum 57 will first close the switch S', then open the switch S³, and then close the switch S² in rapid succession. The cams will then hold the switches S' and S² closed 70 and permit the switch S³ to remain open until the drum 57 completes one rotation whereupon all three switches will be restored to their original normal positions, that is the switches S' and S² open and the 75 switch S³ closed. As soon as the switch S' is closed current from the direct current circuit 1 will flow directly through the wires 30 and 31 and switch S' to the pole changer 4, thus causing energization of the 80 transformer 7 as long as the switch S' remains closed. The opening of the switch S³ cuts off current from the battery M causing the switch G to open. The closing of the switch S² permits low potential current 85 from the secondary coil S of the transformer 7 to flow through the wire 10, push button switch 65, bell B, wire 11, switch S², and wire 12 back to the coil, thus completing a circuit through the bell B as long 90 as the switch S² and push button switch 65 remain closed. The cams 58, 59 and 60 are so arranged that after rotation of the drum 57 has commenced and the switches S' and S² closed, and the switch S³ open, 95 all three switches will remain in such positions until the drum 57 completes one rotation. The teeth on the wheel 52 and the speed of vibration of the breaker bar 40 are so arranged that the wheel 52 will 100 make one rotation in about one and one half seconds. It is obvious that if the push button 105 switch 65 is opened in a less time than required to make one revolution of the ratchet wheel 52, that the bell would ring only for the time the circuit was closed at 65. Regardless of the time that the switch 65 is held closed, however, the pole changer, having once been started, will cause the ratchet wheel 52 to complete one rotation. This 110 is caused by the fact that as soon as rotation of the wheel 52 and drum 57 is commenced, the switch S' is closed, completing a circuit through this switch to the pole changer. The cam 58 is arranged to close 115 the switch S' immediately upon commencement of rotation of the drum 57. The parts are so arranged that the switch S³ opens in about $\frac{3}{2}$ of a second after the closing of the switch S', and the switch S² closes in about 120 $\frac{3}{2}$ of a second after the opening of the switch S³. It is obvious that the consumption of the current from the battery M will be very slight because the switch S³ opens in a fraction of a second after the closing of the push button 65, thus cutting off flow of current from the battery M. It is 125 obvious also that if the push button switch 65 is held closed throughout the completion of one rotation of the ratchet wheel 52, 130

that said wheel will commence another rotation, and repeat as long as the push button switch 65 is held closed.

In Fig. 3 I have shown a modified form of device. It will be noted that in this form the switch G is dispensed with and the wires 17 and 15 are led to the magnet 16' which is located near the switch S'. The magnet 16' takes the place of the magnet 16; and the construction of the switch S' is slightly altered as shown, one of the members being extended to lie near the pole piece 23' of the magnet 16' so that energization of the magnet will close the switch S'. It will be noted that this construction is slightly different from that shown in the preferred form. Practically the only difference is that the switch G is dispensed with and the magnet 16' in place of the magnet 16 is used to close the switch S' when the push button 65 is first pressed. As soon as the switch S' is closed the pole changing apparatus starts to turn the drum 57, and this movement of the drum serves to hold the switch S' closed in the same way as in the operation of the preferred form. In the preferred form, the magnet 16 closes the switch G which starts the pole changing apparatus, and this immediately closes the switch S'. In the modified form the switch S' is closed directly by the magnet 16'.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent is:

1. In a system of the class described; a transformer; a relatively high potential direct current circuit having in series therewith the primary winding of the transformer, a current interrupter, and a switch (S¹) normally open; a signaling circuit having in series therewith the secondary winding of the transformer, a control switch, a signaling device, and a switch (S²) normally open; a shunt circuit on the signaling

circuit including a source of potential, the control switch, and a switch (S³) normally closed; means operated by flow of current through the shunt circuit for closing the switch (S¹); and means operated by the current interrupter for closing switches (S¹) and (S²), and opening switch (S³), and then restoring said switches to their normal positions.

2. In a system of the class described; a transformer; a relatively high potential direct current circuit having in series therewith the primary winding of the transformer, and a switch (S¹) normally open; a signaling circuit having in series therewith the secondary winding of the transformer, a control switch, a signaling device, and a switch (S²) normally open; a shunt circuit on the signaling circuit including a source of potential, the control switch, and a switch (S³) normally closed; means operated by flow of current through the shunt circuit for closing the switch (S¹); and simultaneously operated means operated by flow of current through the high potential direct current circuit for closing switches (S¹) and (S²), and opening switch (S³), and then restoring said switches to their normal positions and interrupting the primary circuit.

3. In a system of the class described; a transformer; a relatively high potential direct current circuit having in series therewith the primary winding of the transformer, a current interrupter, and a switch (S¹) normally open; a signaling circuit having in series therewith the secondary winding of the transformer, a control switch, a signaling device, and a switch (S²) normally open; a shunt circuit on the signaling circuit including a source of potential, the control switch, and a switch (S³) normally closed; means operated by flow of current through the shunt circuit for electrically connecting the terminals of switch (S¹); and means operated by the current interrupter for closing switches (S¹) and (S²), and opening switch (S³), and then restoring said switches to their normal positions.

In witness whereof, I have hereunto set my hand and seal this 21st day of October, 1920.

CHARLES A. NASH. [L. S.]
